SLAG POCKET

Elmer E. McVey, John L. Tatman, and William C. Wallis, Steubenville, Ohio

Application May 25, 1944, Serial No. 537,224

4 Claims. (Cl. 263—45)

1

This invention relates to slag pockets and particularly slag pockets of metallurgical furnaces such as regenerative open hearth furnaces. The slag pockets of regenerative open hearth furnaces are chambers at the bottoms of the up- and downtake flues. The gases are conducted to and from the furnace through the slag pockets and during operation of the furnace solid matter (slag) is deposited in the pockets. The slag builds up in the pockets and ultimately has to be cleaned out.

The cleaning out of slag pockets has been most difficult as the slag when deposited is in such condition that the slag particles fuse together into a more or less solid mass which adheres to the pocket walls. The cleaning out of a slag pocket prior to the present invention has entailed a great deal of work in breaking up and digging out the slag and repairing the pocket walls which are partially or largely destroyed in the cleaning out process.

We provide a slag pocket obviating the disadvantages of slag pockets as heretofore known and enabling cleaning out of the slag with great facility. We provide for bodily removing the slag in one or more large masses or blocks with a minimum of breaking up. Our slag pocket preferably comprises a chamber having inner and outer structurally separate wall portions with the inner wall portion arranged to contact the slag deposited in the pocket and to be removed with the slag when the pocket is cleaned out. The inner wall portion is a temporary wall portion structurally separate and preferably somewhat spaced from the opposed outer wall portion which is preferably permanent. We find it desirable to dispose non-structural material such as sand or the like between the wall portions.

We further provide a slag pocket comprising a chamber having walls the portions of which above the normal maximum slag level are permanent and the portions of which below the normal maximum slag level have permanent outer parts and temporary inner parts arranged to contact the slag deposited in the pocket and to be removed with the slag when the pocket is cleaned out. Our slag pocket also preferably has an end wall removable with the slag. Desirably the slag pocket may comprise a supporting framework including a generally horizontal wall support disposed above the normal maximum slag level, a permanent upper wall structure above and supported by said support and a double wall structure below said support comprising an outer permanent wall portion and an inner temporary wall portion arranged to contact the slag deposited in

2

the pocket and to be removed with the slag when the pocket is cleaned out.

We also provide a slag pocket comprising a chamber having a wall extending thereacross to divide the pocket into a plurality of slag receiving spaces, said wall being fragile to facilitate separate removal of the slag in the respective spaces and being adapted to be destroyed upon such removal. Preferably the wall extending across the pocket comprises loosely laid up structural masses such as old brick laid up dry so that such wall is removed with the slag when the pocket is cleaned out.

We still further provide a slag pocket having 15 double side wall portions and a wall extending thereacross, the inner parts of the double side wall portions and the wall extending across the pocket being arranged to contact the slag deposited in the pocket and to be removed with the slag when the pocket is cleaned out.

Other details, objects and advantages of the invention will become apparent as the following description of a present preferred embodiment thereof proceeds.

25 In the accompanying drawings we have shown a present preferred embodiment of the invention, in which

Figure 1 is a vertical cross-sectional view through the gas and air slag pockets of a regenerative open hearth furnace;

Figure 2 is a horizontal cross-sectional view taken on the line II—II of Figure 1; and

Figures 3 and 4 are perspective more or less diagrammatic views illustrating how slag is removed from our improved slag pocket.

30 Referring now more particularly to the drawings, there are shown in Figures 1 and 2 a gas slag pocket 2 and an air slag pocket 3 of a regenerative open hearth furnace, which furnace except for the construction of the slag pockets may be of conventional type. A flue 4 communicates with the gas slag pocket 2 and a flue 5 communicates with the air slag pocket 3.

The furnace is constructed with a supporting 45 framework 6 which comprises uprights 7 and horizontal members 8. An upright 9 and horizontal members 10 are positioned between the slag pockets 2 and 3. The uprights 7 carry channels 11 which cooperate with the upper horizontal member 10 to support the brick of an arch 12 over the gas slag pocket 2 and an arch 13 over the air slag pocket 3.

The uprights 7 and 9 also carry water cooled angles 14 which support the wall portions 15 of the slag pockets which lie thereabove. The arches 12 and 13 and the wall portions 15 above

the angles 14 are of permanent structure and are built up of refractory brick.

Below the angles 14 the slag pocket walls have outer permanent portions 16 and inner temporary portions 17. The inner temporary portions 17 are made of refractory brick and the outer portions 16 are also of brick, preferably refractory, although in some cases a cheaper brick may be used. The temporary inner wall portions 17 are arranged to contact the slag deposited in the pockets and to be removed with the slag when the pockets are cleaned out as will presently be described. Wall portions 16 and 17 are structurally separate and are preferably spaced apart as shown, non-structural material such as sand or the like 18 being disposed therebetween.

The slag pocket 2 has a permanent inner end wall 19 of refractory brick and the slag pocket 3 has a permanent inner end wall 20 of refractory brick. The outer end walls of the slag pockets 2 and 3 are shown at 21 and 22, respectively. These walls are built up of refractory brick and, like the wall portion 17, are arranged to contact the slag deposited in the pockets and to be removed with the slag when the pockets are cleaned out.

The angles 14 are disposed slightly above the normal maximum slag level, which is roughly the level of the top of the non-structural material 18. It is contemplated that normally the arches 12 and 13 and the wall portions 15, 16, 19 and 20 are not disturbed in cleaning out of the slag which accumulates in the slag pockets, being removed with the slag as will be described.

The pockets preferably have walls extending thereacross to divide them into a plurality of slag receiving spaces, such walls being fragile to facilitate separate removal of the slag in the respective spaces and being adapted to be destroyed or removed with the slag when the slag is cleaned out. One such wall is shown fragmentarily at 25 in Figures 3 and 4. It is built up of old brick laid up dry. Another such wall is indicated at 24.

When it is desired to clean out the slag pockets the wall portions 17 are broken through adjacent the top of the non-structural material 18 and also adjacent the end walls 21 and 22. This may be done by using a pneumatic drill. Figure 3 is a diagrammatic perspective view through the air slag pocket 3 but as though the wall 22 had been removed, thus exposing the interior of the pocket. When the wall portions 17 have been broken through as above mentioned the slag together with the wall portions 17 and the walls 21 and 22 may be removed in large chunks or blocks without the necessity of the slag being broken up and shoveled out. Preferably the slag in each of the pockets is removed in three blocks, the blocks being preferably determined by the transverse walls 25 and 24. The wall 25 may be broken up by the pneumatic drill and a chain or cable may be placed around the outer mass or block of slag and the slag may be pulled out by any suitable source of power. The second mass or block of slag between the walls 25 and 24 may be similarly removed, and, finally, the third mass or block of slag between the wall 24 and the inner wall of the pocket may be similarly removed. Due to the provision of the non-structural material 18 between the inner wall portions 17 and the outer permanent lower wall portions 16 the chain or cable may easily be laid in between the wall portions 17 and 16. Figure 4 shows at 23 how the wall portions 17 are broken through adjacent the top of the non-structural material 18

and just below the water-cooled angles 14. This provides an opening into the space occupied by the non-structural material 18. The slag is removed in roughly cubical chunks five to six feet on an edge. In Figure 4 one such chunk has been removed and the work toward preparing the second chunk for removal is under way.

After the slag pockets have been cleaned out the temporary wall portions 17, 24 and 25 and the end walls 21 and 22 are rebuilt, the permanent portions 12, 13, 15, 16, 19 and 20 remaining undisturbed unless their repair is necessary for some other reason.

While we have shown and described a present preferred embodiment of the invention it is to be distinctly understood that the invention is not limited hereto but may be otherwise variously embodied within the scope of the following claims.

We claim:

- 20 1. A slag pocket comprising a supporting framework including a generally horizontal wall support disposed above the normal maximum slag level, a permanent upper wall structure above and supported by said support and a double wall structure below said support comprising an outer permanent wall portion and an inner temporary wall portion arranged to contact the slag deposited in the pocket and to be removed with the slag when the pocket is cleaned out.
- 25 2. A slag pocket having an upper portion and a lower portion, the lower portion of the wall having a permanent outer part and a temporary inner part adapted to be removed with the slag and the upper portion of the wall being permanent and having its inner part disposed directly above the temporary inner part of the lower portion and with its bottom in contact with the top of the temporary inner part of the lower portion.
- 30 3. A slag pocket having a permanent generally upright wall portion relatively thin at its lower part and relatively thick at its upper part and projecting farther inwardly at its upper part than at its lower part and a temporary wall portion adapted to be removed with the slag disposed directly beneath the inwardly projecting upper part of the permanent wall portion, the inner face of the temporary wall portion being flush with the inner face of the upper part of the permanent wall portion.
- 35 4. A slag pocket having a base and an in situ built up wall extending upwardly continuously from the base and having an upper portion and a lower portion, the lower portion of the wall having a permanent outer part and a temporary inner part adapted to be removed with the slag, the upper portion of the wall being permanent.
- 40 5. A slag pocket having a base and an in situ built up wall extending upwardly continuously from the base and having an upper portion and a lower portion, the lower portion of the wall having a permanent outer part and a temporary inner part adapted to be removed with the slag, the upper portion of the wall being permanent.
- 45 6. A slag pocket having a base and an in situ built up wall extending upwardly continuously from the base and having an upper portion and a lower portion, the lower portion of the wall having a permanent outer part and a temporary inner part adapted to be removed with the slag, the upper portion of the wall being permanent.
- 50 7. A slag pocket having a base and an in situ built up wall extending upwardly continuously from the base and having an upper portion and a lower portion, the lower portion of the wall having a permanent outer part and a temporary inner part adapted to be removed with the slag, the upper portion of the wall being permanent.
- 55 8. A slag pocket having a base and an in situ built up wall extending upwardly continuously from the base and having an upper portion and a lower portion, the lower portion of the wall having a permanent outer part and a temporary inner part adapted to be removed with the slag, the upper portion of the wall being permanent.
- 60 9. A slag pocket having a base and an in situ built up wall extending upwardly continuously from the base and having an upper portion and a lower portion, the lower portion of the wall having a permanent outer part and a temporary inner part adapted to be removed with the slag, the upper portion of the wall being permanent.

Patent No. 2,476,614

ELMER E. McVEY ET AL.

It is hereby certified that error appears in the printed specification of the above numbered patent requiring correction as follows:

Column 4, line 30, after the word "pocket" insert *having a wall*;
and that the said Letters Patent should be read with this correction therein that the same may conform to the record of the case in the Patent Office.

Signed and sealed this 3rd day of January, A. D. 1950.
